CLAIM

The ornamental design for a metal-air fuel cell for lamp, as shown and described.

DESCRIPTION

FIG. 1 is a front elevational view of a metal-air fuel cell for a lamp, showing our new design, the rear elevational view being the same;

FIG. 2 is a side elevational view thereof, the opposite side elevational view being a mirror image;

FIG. 3 is a top plan view thereof.

FIG. 4 is a bottom plan thereof.

FIG. 5 is a perspective thereof.

Any portion of the drawing disclosure shown in broken lines is for illustrative purposes only and forms no part of the claimed design.

FIG. 1***FIG. 3***FIG. 2

FIG. 4

FIG. 5UNITED STATES PATENT AND TRADEMARK OFFICE
CERTIFICATE OF CORRECTION

PATENT NO. : D 320,190

DATED : September 24, 1991

INVENTOR(S) : Robert P. Hamlen and Thomas J. Zoltner

It is certified that error appears in the above-identified patent and that said Letters Patent is hereby corrected as shown below:

On the Title page,

Left-hand column, Item [75], change
"Inventor: Robert P. Hamlen, Bernardsville, N.J." to
-- Inventors: Robert P. Hamlen, Bernardsville, N.J.;
Thomas J. Zoltner, Denville, N.J. --

Signed and Sealed this

Fifteenth Day of June, 1993

Attest:

MICHAEL K. KIRK

Attesting Officer

Acting Commissioner of Patents and Trademarks
